UNITED STATES PATENT OFFICE

JOHN VOYTKO, OF STREATOR, ILLINOIS

SEWER TILE

Application filed December 10, 1928, Serial No. 324,900.

This invention has relation to tiles for the construction of sewer pipes and other conduits of large size and has for its object the provision of a tile of sector formation, having improved means for the solid and substantial connection in series to form a cylindrical tubular structure, which may be built up and completed in cylindrical sections before being laid in place.

10 The invention consists in the novel construction and combination of parts herein-after described and claimed.

In the accompanying drawings, illustrating a preferred embodiment of my invention. 15 Figure 1 is an end view of a tube or conduit built up of the tiles constituting my invention;

Figure 2 is an enlarged view of a portion of the conduit showing the construction and 20 mode of fitting lengths in the tile sectors;

Figure 3 is a fragmentary sectional view showing the right hand end portion of sector 1;

Figure 4 is a sectional view on line 4—4 25 of Figure 2.

The tile is of the general form of the sector of a circle and is composed of burnt clay of the usual character. The several connected sectors forming the circle or pipe are generally designated by the reference character A, and for purpose of detailed description with more specific reference to Figure 2, adjacent tile sectors are designated by the reference numerals 1 and 2. Each sector for the purposes of the invention is of hollow construction with longitudinal channels 3 crossed diagonally by webs 3a which impart the requisite strength and stability to the structure. The dimensions of the tile will vary according to the special uses made of it and the required dimensions of the sewer or conduit. Generally, such tile will be three to four feet in length, seven inches in thickness and of a diameter of sixty inches, outside measurement. The conduit may comprise any desired number of sectors which will be controlled by the diameter of the sector and the diameter of the completed pipe or conduit. The construction features constituting the invention reside in the forma-

tion of the jointed adjacent sides of the sectors.

The side edges of the tile sectors are formed with interlocking tongues and grooves, and as shown in detail in Figure 2, the sector 1 is formed at its outer side edge with a semi-dove tailed tongue 4 having its outer surface coincident with the periphery of the sector while a dove-tailed tongue 5 is carried by the side edge of the sector 1 spaced from the semi-dove tailed tongue 4, between the inner and outer edges of the sector. The adjacent inclined faces of the tongues 4 and 5 define a dove-tail groove 4a in the edge wall of the sector 1, while a semi-dove tailed groove 5a is formed at the inner side edge 55 of the sector 1 adjacent the dove-tailed tongue 5.

The meeting side edge of the adjacent tile sector 2 is fashioned with tongue and groove 70 for interlocking association with the adjacent edge of the tile sector 1 and has at its inner side edge a semi-dove tailed tongue 9 received in the semi-dove tail groove 5a and a dove-tailed tongue 8 spaced from the 75 tongue 9 and the outer side edge of the tile sector 2 received in the dove-tailed groove 4a. The adjacent inclined faces of the tongues 8 and 9 form a dove-tailed groove 9 to receive the dove tailed tongue 5, while 80 the semi-dove-tailed groove 8a at the outer side edge of the tile sector 2 receives the semi-dove tailed tongue 4, the interlocking engagement between the side edges of the tile sectors 1 and 2 being clearly illustrated in 85 Figure 2. The relative dimensions of the tongue and groove connections are such that when the tile sectors 1 and 2 are assembled, the outer edge of the tongue 4 abuts the groove 8a, while the outer edge of the tongue 9 abuts the groove wall 5a. The adjacent side and end walls of the tongues 5 and 8 being spaced from the walls of the associated 90 grooves 4a and 9a. The intervening spaces are filled with a binder, such as cement or 95 concrete for the permanent connection of the tile sectors, the binder preventing relative movements in any direction of the associated sectors.

In assembling the sectors to form a tube 100

or conduit, they are moved into position lengthwise of the sectors, the tongues sliding into their respective grooves. The binder of cement or concrete may be introduced into the intervening spaces between the tongues and grooves by the action of compressed air or the like, and moved lengthwise of said spaces to completely fill them while the sectors are being assembled. An additional cement or concrete binder is provided for the joints between the sectors for the provision of relatively deep pockets 6 extending inwardly from the outer ends of the dove-tailed tongues 5 and 8 that register with relatively shallow pockets 7 in the bottom walls of the recesses 4a and 9a. The cement or concrete binder completely filling the pockets as shown in Figure 2, for a more effective seal for the tile sectors. The cement or concrete binder is designated by the reference numeral 10 and completely fills the intervening spaces and pockets present in the joints between the assembled tile sectors.

While there is herein shown and described the preferred embodiment of the present invention, it is nevertheless to be understood that minor changes may be made therein without departing from the spirit and scope of the invention as claimed.

26 I claim:—

27 A tile for the construction of tubes or conduits for sewers and the like, consisting of a sector of burnt clay formed at the sides with dove-tailed tongues and grooves, the intermediate tongues at one side being in staggered relation to the tongues at the other side, and of greater length and width than the grooves, whereby interfitting tongues and grooves are spaced apart on all sides, 35 for the reception of cement fillings, the outermost tongue being formed and adapted to abut against the bottom of the coinciding groove, the intermediate interfitting grooves and tongues being recessed at opposite points 40 to form channels for the reception of cement filling.

45 In testimony whereof I affix my signature.
JOHN VOYTKO.
